UNITED STATES PATENT OFFICE.

NORTON A. NEWDICK, OF COLUMBUS, OHIO, ASSIGNOR TO THE COLODER COMPANY, OF COLUMBUS, OHIO, A CORPORATION OF DELAWARE.

LOADING MACHINE.

Application filed January 22, 1921. Serial No. 439,092.

This invention relates to loading machines, and has for its principal object to provide an efficient yet simply constructed and operative machine for the purpose of loading coal from the face of a mine working and to deposit such coal into mine cars, by means of which the coal, or other analogous material, may be quickly and economically removed from the mine.

Another object of the invention resides in the provision of a machine of this character wherein the gathering and loading mechanisms are mounted upon a common wheeled base unit, in such manner that the machine may be readily adjusted to assume operative positions when the operation of loading is being performed upon curved track-ways, or in tortuous rooms or entries or pillars of a mine, wherein it is necessary that the gathering and loading mechanisms should assume angular positions with respect to one another, the arrangement being such that the discharge end of the gathering mechanism will always be positioned under working conditions over the receiving end of the loading mechanism.

A further object resides in constructing the machine so that the same will be exceptionally convenient and simple to operate, and wherein in all of the various controls thereof are centrally located so that the controls will be at all times within the convenient reach of the operator, this feature being primarily accomplished by eliminating the isolated controls found in many machines of the prior art, reducing the number of such controls, rendering operations largely automatic, and in generally simplifying the machine to the end that the operator thereof will have the various mechanisms and parts under instantaneous and convenient control.

Other objects of the invention reside in a coal loading machine of the character specified wherein a common motor is provided for effecting the operation of the gathering and loading mechanisms; in providing the loading mechanism with an automatically operated clutch, whereby the direction of movement on the part of the loading mechanism will be the same, irrespective of the direction of rotation of the driving motor or the operation of the gathering mechanism; in the provision of a novel and improved structure for supporting the rear end of the gathering

mechanism in conjunction with the forward portion of the base unit, in order that said gathering mechanism will be permitted to swing laterally and horizontally across the floor of a mine, to have the necessary vertical up and down movement to compensate for irregularities in the mine floor and to permit the driving or power imparting connections for the gathering mechanism to pass through the articulately related joints for allowing such bodily movement on the part of said gathering mechanism; and finally in providing the base unit with a swivel base plate or platform upon which the loading mechanism and the motor therefor is mounted, said plates serving to provide means for conveniently permitting of the lateral shifting of the loading mechanism and also to maintain proper driving relation between the motor and said mechanism.

With these and other objects in view, as will appear as the description proceeds, the invention accordingly consists in the novel features of construction, combinations of elements and arrangements of parts, hereinafter to be fully described and pointed out in the appended claims.

In the accompanying drawings, forming a part of this specification, and in which similar characters of reference denote like and corresponding parts throughout the several views thereof:

Figure 1 is a side elevation of the improved loading machine comprising the preferred form of the present invention.

Figure 2 is a top plan view thereof,

Figure 3 is a side elevation showing fragmentarily the rear portion of the gathering mechanism, the base unit, and the forward part of the loading mechanism, parts being broken away and shown in section to disclose more clearly underlying and interior structure,

Figure 4 is a top plan view of the base unit and showing more particularly the position of the main driving motor and associated power imparting connections,

Figure 5 is a vertical longitudinal sectional view taken through the gathering mechanism and disclosing in side elevation the means for shifting the gathering mechanism laterally,

Figure 6 is a plan view of said lateral shifting mechanism,

Figure 7 is a transverse cross-sectional view taken on the plane disclosed by the line 7—7 of Figure 5.

Figure 8 is a vertical transverse sectional view disclosing the compound pivotal mounting for the rear end of the gathering mechanism.

Figure 9 is a detail sectional view disclosing the clutches and driving mechanism for effecting the operation of the lateral shifting mechanism.

Figure 10 is a detail plan view setting forth the base unit and the movable platform carried thereby.

Figure 11 is a horizontal sectional view showing the automatic clutch construction for causing the loading conveyor to travel in but one direction.

Figure 12 is a side elevation of said automatic clutch.

Figure 13 is a sectional view disclosing the slip or overload clutch.

Figure 14 is a detail view disclosing the mechanism for vertically adjusting the loading conveyor.

Figure 15 is a detail vertical section taken through the hopper and disclosing the noise reducing construction thereof, and

Figure 16 is a detail section taken on the line 16—16 of Figure 9.

Referring more particularly to the details of the invention, use is made of a loading machine 1 which, in this instance, is formed to include a wheeled truck or base unit 2, which is adapted to operate over a suitable track-way 3 so that the loading machine as a whole may be rapidly and easily transported and quickly brought from one position of operation to another within the shortest time possible. This truck is essentially of rectangular form and includes side and end members 4 and 5 respectively, the former being provided with journal boxes 6 on which are rotatably mounted the ends of axles 7 which carry the usual track engaging wheels 8, adapted for operation over the track-way 3. The truck 2 is provided adjacent to the forward end member 5 thereof with a fixed clevis 9 which is adapted to receive the apertured forward end of a horizontally shiftable platform which in this instance is in the form of a base or bed plate 10, a pin 11 being arranged so as to pass through openings provided in the clevis and through a registering opening provided in said plate, in order that the latter may be pivotally mounted or swiveled for lateral swinging movement with respect to the frame of the truck 2. To further effect the support of the platform or plate 10, the rear portion of the truck 2 is provided with a plurality of brackets 12, which carry anti-friction rollers 13. These rollers are so positioned as to receive and support the rear portion of the plate 10. Also, the brackets 12 are provided with over-

hanging lips 14, which are arranged so as to extend over the upper surface of the plate 10 so as to prevent undue upward movement on the part of the latter and the mechanism carried thereby. To shift the plate 10 laterally, the under surface thereof is provided with an arcuate rack 15, which engages with a worm 16 carried by a transversely journaled shaft 17 positioned in the truck 2, the outer ends of the shaft 17 being provided with hand wheels 18, whereby said shaft may be rotated readily to effect the shifting of the bed plate. It will be apparent that by the provision of the rollers 13 and by the worm shaft construction, the shifting of the bed plate and its associated mechanism may be conveniently effected by manual means and without difficulty, and also by the provision of the worm 16 said bed plate will be locked against movement in any of its adjusted positions.

Mounted upon the bed plate 10 is a prime mover which in this instance is in the form of an electrical motor 19, said motor being firmly bolted or otherwise secured to base enlargements or pads 20 integrally formed with the bed plate 10. The armature shaft of the motor is preferably equipped with a spur pinion 21, which meshes with an enlarged gear 22 forming a part of a slip or overload clutch construction 23 which will be hereinafter more fully described. The gear 22 is adapted to drive a transversely extending shaft 24, which is mounted in bearings 25 carried by the bed plate, said bearings being firmly bolted to pads 26 formed with the upper surface of the shiftable base plate. Preferably, the shaft 24 extends in parallelism with the armature shaft of the motor 19, and has its end, opposite to the end associated with the gear 22, provided with a beveled pinion or an equivalent 27. This pinion 27 is adapted to mesh with a mitre gear 28, which is fixed to one end of a forwardly and longitudinally extending shaft 29, the latter shaft is mounted in bearings 30 carried by the base or bed plate 10. The forward end of the shaft 29 is equipped with a fixed bevel pinion 31, which meshes with a bevel gear 32, rigidly provided upon the outer end of a relatively short transversely extending shaft 33.

The shaft 33 is mounted for rotation in one of a pair of bearings 34 carried by the forward portion of the bed plate 10, and in this instance the bearing 34 receiving the shaft 33 is of elongated formation, in order that the gear 32 will be positioned on the outside of the pinion 31, a feature which is provided for sake of clearness and to prevent the gear 32 from striking adjacent stationary parts. Also, the shaft 33 is preferably mounted for rotation within roller bearings 35. A pinion 36 is fixed to the inner end of a shaft 33 and is adapted to mesh with a bevel gear 37 provided upon the lower end of a vertical shaft 38.

38. This shaft extends upwardly through a hollow saddle member or pedestal 39 and has its upper end provided with a fixed sprocket 40 with which the flight carrying endless gathering belt or chain 41 is adapted to co-operate. The pedestal 39 is provided at its lower end with transversely extending enlargements 42, which are adapted to be suitably clamped around the bearing brackets 34, 10 in order that said pedestal will be permitted to swing vertically about the horizontal pivot provided by the aligned bearings 34. It will be observed that the shaft 33 is concentric or in other words axially positioned with respect to the bearings 34, hence is in a position so that the pinion 36 thereof will constantly mesh and remain in engagement with the gear 37 irrespective of vertical oscillations on the part of the pedestal 39 and associated mechanism. By this construction it will be apparent that power may be directly applied to the sprocket 40 without interfering with the vertical adjustments of the gathering mechanism, which adjustments are 25 made possible by the construction disclosed.

The gathering mechanism, indicated generally by the letter A consists essentially of an elongated metallic frame 43, the latter being formed to include a depressed forward 30 or nose portion 44, an upwardly inclined and rearwardly extending intermediate portion 45, and a substantially horizontal elevated discharge end 46. This end is apertured so as to receive the shaft 38 and the 35 upper end of the pedestal 39, and also carries a fixed depending sleeve 47, which is so positioned as to receive the upper end of the pedestal 39 and to rest upon a roller bearing 48 provided upon an annular flange 40 enlargement 49 formed with the pedestal. By this construction it will be manifest that the pedestal 39 serves as a vertical pivot for the rear end of the gathering mechanism, and about which pivot the gathering mechanism 45 as a whole is permitted to bodily oscillate in lateral directions so as to be capable of effecting back and forth sweep movements across the floor of a mine. It will be manifest, therefore, that the gathering mechanism 50 is mounted upon a compound pivot construction, wherein the upper end of the pedestal serves as a vertical pivot and the bearings 34 serve as a horizontal pivot. By this construction of pivotal mounting, the gathering mechanism 55 is capable of being fed by arcuate movements in horizontal directions into engagement and co-operation with the material to be loaded and by the provision of the horizontal pivot, the gathering mechanism may 60 oscillate vertically so that the nose portion thereof may be accommodated to irregularities or roughness in the surface upon which it is traveling. Moreover, not only is a strong durable pivotal construction provided for the 65 gathering mechanism but in addition the

driving shafts thereof are so correlated and positioned that the same are capable of passing directly through the pivotal connection without in any way effecting the articulated movements thereof.

70

The nose portion of the gathering mechanism is of flat construction, in order that the same may be forced over a mine floor in such manner as to bury itself beneath the material to be loaded, and to permit such material to 75 drop, gravitate or to be readily forced upon the upper surface of the nose portion, whereby the material will be engaged by traveling flight arms 50, which are carried by the endless belt of the gathering mechanism and are 80 adapted to run horizontally and longitudinally within spaced run-ways 51 formed in the frame 43, said run-ways being primarily defined by means of the bottom of the frame, the central and longitudinally extending 85 housing 52, and the sides 53. As shown in Figure 7, said flights are connected with or form a part of the chain 41 and hence are adapted to be driven by the sprocket 40, around which the chain 41 is trained. Also, 90 the forward run of the chain passes around a forward sprocket 54, carried by the nose portion of the frame, the latter sprocket serves as a guide, and directs the flight arms into the material to be loaded. It will be apparent 95 that the motor 19 is of the reversible type, and accordingly the gathering chain may be caused to travel in either direction, a feature which enables the coal or other material to be loaded into the machine by way of either 100 of the run-ways 51 and advanced alternately, at the will of the operator, through said run-ways in the line of draft of the machine. The chain 41 is guided in its movements by means of longitudinal guides 55 formed with the 105 housing 52, and preferably the inner ends of the flight arms are provided with rollers 56, which operate within the guides 55 and serve to eliminate undue friction between the flight arms, the chain and the guides 55 when the 110 gathering chain is operating under load conditions.

To feed the gathering mechanism laterally so that the same may be gradually fed in an oscillatory manner into engagement with the 115 material to be loaded, the frame 43 is adapted to carry a second electrical motor 57, which in combination with the motor 19, are the only motors utilized by the machine. This motor 57 has its armature shaft equipped with a 120 worm 58, which meshes with a worm gear 59 fixed upon a transversely extending shaft 60, said shaft and worm gear being mounted for rotation within a suitable case 61 formed with the motor 57. The ends of the shaft 60 project beyond the case 61, and are equipped with loose sprockets 62 and 63 located on opposite sides of the case 61. The sprocket 62 has trained thereabout an endless chain 64, which chain is arranged to extend so as to 125 130

be trained over a second sprocket 65, the latter being mounted for rotation upon a fixed shaft 66 carried by the housing 52. This shaft 66 carries a drum 67 with which is connected a side feed chain 68. The sprocket 63, in turn, is provided with an endless chain 69, which is trained over a second sprocket 70, loosely mounted upon a forward stationary shaft 71, the latter shaft being positioned so as to rotatably receive a forward chain drum 72. This latter drum is also adapted to have secured thereto one end of a second side feed chain 73, which extends in an opposite direction to the chain 68 and is adapted to be employed to shift the feeding mechanism in an opposite direction. As shown in the drawings the chains 68 and 73 pass from their respective drums and are trained around superimposed spooling drums 74, which latter are loosely mounted upon a stationary shaft 75 carried by the housing 52 at a point above the shaft 71. From these superimposed drums, the side feed chains extend downwardly and pass around guide pulleys 76, from which the chains extend in opposite directions, as is shown in Figure 2, in order that the outer portions of the chains may pass around fixed guides or jacks 77, and after passing around these jacks the free or outer ends of the side feed chains are secured as at 78 to the frame of the gathering mechanism.

By this construction it will be apparent that when one of the side feed chains is wound about its respective drum the gathering mechanism as a whole will be shifted in the direction wherein the chain length has been shortened, or in other words, by winding the chain around its drum the gathering mechanism is pulled laterally so that its nose portion will be maintained constantly in engagement with the material to be loaded. It will be observed that worm gearing has been provided for effecting the operation of the winding drums. This form of power transmission has been employed for the purpose of imparting a relatively slow and powerful side feeding movement to the gathering mechanism. After the machine has been fed its maximum distance in any given direction, the motor 57 is reversed, thereby causing the other chain to be wound about its respective drum, to oscillate the gathering mechanism in the opposite direction. Any suitable means may be provided for advancing the machine longitudinally so that its nose portion will be kept beneath the material to be loaded. This is preferably accomplished by means of mine locomotives, which are positioned to the rear of the truck 2, and are capable of forcing the truck and the gathering mechanism beneath the coal to be loaded either by continued effort or by a series of jolts or blows. In order to automatically feed the gathering mechanism laterally, the

shaft 60 has its ends reversely threaded at 79 to receive shiftable clutch members 80 which are provided with internally threaded bores to receive the threaded ends of the shaft 60. The said members 80 are provided with clutch faces 81 which are adapted to be moved into and out of interlocking engagement with similar clutch faces 82 provided upon the outer sides of the sprockets 62 and 63. The ends of the shaft are provided with fixed collars 82' which are positioned to limit the outward movement of the clutch members and also to maintain the sprockets 62 and 63 secure against longitudinal movement. Weights or their equivalents 82^a are provided in connection with rings 82^b, loosely situated in annular grooves provided in the clutch members, and these weights serve in operation to prevent rotation of the clutch members when the shaft is being rotated to slide the members. By this arrangement the direction of rotation of the chain drums is automatically taken care of without resorting to the use of manually operated clutches, since the rotation of any desired drum may be effected by merely governing the rotation of the motor 57. Thus when the motor is operating in one direction, we will say, the drum 67 will be rotated to wind its chain 68 thereabout, when this occurs the drum 72 will be automatically released by virtue of the shaft construction 60, thereby permitting the chain wound thereabout to be loosely drawn off of said drum 72 when the chain 68 is tightened or wrapped around its drum 67. The reverse of course is true when the power of the motor 57 is directly applied to the chain drum 72, that is, the drum 72 is positively rotated, while the drum 67 is automatically released. By this construction it will be observed that convenient, simple and positive means are provided for effecting the back and forth sweep movements on the part of the gathering mechanism, and a construction is provided which will effectually serve to maintain the nose portion and flight construction of the gathering mechanism in loading cooperation with the blown down material at the face of a working. The control 83 for the motor 57 is directly carried by the truck 2, and is situated in adjacent relationship with respect to the control 84 for governing the operation of the motor 19, and also, the controls are situated so as to be immediately adjacent the controlling lever 85 for the clutch construction 23. By virtue of these three controls the operation of the entire machine can be readily governed, and in fact, the operation of the machine for the greater portion of time can be governed simply by means of the controls 83 and 84, since it is only on infrequent occasions that the clutch construction 23 need be operated by the lever 85. This results in centralizing the controls of the machine and by the provision

of the automatic features, isolated hand controls have been eliminated.

The loading machine as a whole is adapted to be transportably mounted upon the track-way 3, however, when in operation the forward nose portion of the machine projects in advance of the track-way 3, which latter is terminated to the rear of the working or the material to be loaded. This results in permitting the nose portion to directly ride over the floor of the mine without being engaged by the rails formed in the track-way, and enables the machine to successfully load coal without being impeded in its travel. 10 However, to transport the machine from one place of operation to another, it is desirable that the forward portion of the gathering mechanism should be mounted upon wheels capable of riding over the track-way 3, as such a construction admirably serves to eliminate sway or vibration in the machine, to enable the same to negotiate short or sharp curves, and greatly aids to its general stability and freeness from undue swaying 15 movement. To this end, the under portion of the gathering frame is equipped with a pony truck 86, which when the machine is engaged in actual loading, is carried by the under part of the frame 43. Any suitable means 20 may be employed for positioning the truck 86 in the manner disclosed in Figure 1, such for example, as a chain and drum construction 87. However, when the machine is being transported from position to position about a mine, the pony truck is positioned so as to ride over the rails of the track-way 3 and is swivelly connected with the forward end of the gathering frame by means of an adjustable king bolt 88, which is adapted to have 25 its lower end suitably socketed within a bearing provided in the pony truck. While not employed for establishing a swivel connection between the gathering frame and pony truck, the king bolt is elevated so as to be out of the 30 way of the gathering mechanism proper.

In view of the foregoing it is believed that the operation of the gathering mechanism will be clearly understood, and that its construction and principles of operation will be 35 apparent to those skilled in the art. The rear end of the gathering frame is positioned so that material discharged from engagement with the gathering frame by the flight arms 50 will be deposited within the forward 40 end of a loading hopper 89, which latter forms one of the essential parts of the loading mechanism B. This hopper is preferably formed from structural steel and is provided with a widened forward portion which is capable of 45 receiving the discharge end 46 of the gathering frame in all working positions of angularity which the gathering and loading mechanisms may assume with respect to each other. From its widened forward portion 50 the hopper extends rearwardly to provide an

angularly and upwardly extending portion 90, which terminates in a substantially horizontal, longitudinally extending and overhanging discharge end 91, the latter being formed to project some distance to the rear 55 of the truck 2, in order that its discharge end may overlie a mine car or an equivalent 92, which is adapted to be positioned beneath the discharge end of said hopper so as to be capable of receiving the material discharged 60 therefrom. To effect the support of the hopper, the depressed forward end 93 of the bed plate 10 is provided with suitable bearings 94, in which is journaled a transversely extending shaft 95. This shaft is adapted to be received within openings provided in the sides of the hopper, and by this construction the said shaft 95 will serve as a horizontal supporting pivot for the hopper, which will allow the hopper to be adjusted vertically. 65 Also, the shaft 95 is equipped, inside of the hopper, with sprockets 96, over which are trained spaced conveyor chains 97, said chains being connected by means of transversely extending cross flights 98, which are adapted to travel over the floor 99 of the hopper when the upper run of the flights is moving in a rearward direction, by this construction the chain will be so positioned that the forward run thereof will advance in the line of draft 70 of the machine over the bottom of the hopper. Also, the rear overhanging end of the hopper is provided with a transversely extending shaft 100, which carries fixed sprockets over which the chains 97 are trained, and power is 75 imparted to the shaft 100 from the motor 19, in a manner to be hereinafter more fully explained so as to effect the operation of the loading conveyor as a whole. Manifestly, material discharged into the hopper will be 80 engaged by the rearwardly moving portions of the loading conveyor, and will be conducted out of said hopper by said conveyor and discharged into the underlying mine car 92, by means of which the loaded coal may be suitably transferred to various positions of appropriate discharge. 85

To impart power to the loading conveyor, the gear 22 of the clutch construction 23 is provided with a sprocket 101, which sprocket 90 is directly driven from the motor 19, and is independent of the relief or slippage afforded by said clutch construction. Trained over this sprocket 101 is an endless chain 102, which is directed so as to pass around a sprocket 103, the latter carrying a hub 104 which is loosely mounted upon a stud shaft 105 projecting from the side of the loading frame. The hub 104 carries a second sprocket 106, and also a gear 107, the construction being 110 such that the two sprockets 103 and 106 and the gear 107 will rotate as a unit. Extending in parallelism with the shaft 105 is a second stud shaft 108, upon which is loosely mounted a sprocket 109, and an endless chain 110 is 115

120

125

130

arranged so as to pass over the sprockets 106 and 109 so that said sprockets will rotate together and in the same direction. Similarly, the stud shaft 108 is equipped with a gear 111 which is adapted to mesh with the teeth of the gear 107, but it is obvious that the gear 111 rotates in a direction opposite to that of the gear 107. The sprocket 109 and the gear 111 carried by the stud shaft 108 are provided with hubs 112 and 113 respectively, which hubs are provided with clutch teeth arranged in opposed relationship with each other. Loosely mounted upon the stud shaft 108 and confined between the hubs 112 and 113 is an automatically shiftable sprocket 114, whose hub 115 is provided with oppositely disposed teeth designed for selective cooperation with the teeth of the gear 111 and the sprocket 109. It will be apparent that by reversing the direction of rotation of the motor 19, the direction of movement on the part of the chain 102 will also be reversed, and accordingly this automatic clutch construction is provided so that the direction of movement of the forward run of the loading conveyor will be in one way only, that is, in a rearward draft or discharging direction. With this object in view it will be apparent that when the chain 102 is driven so that the hub 104 rotates in the direction of the arrow C, the gear 111 will be rotated so that its teeth will positively mesh with the teeth of the hub of the automatically shiftable sprocket 114, thereby causing the drive chain 115' which passes around the sprocket 114 and around a similar sprocket provided upon the shaft at the extreme rear end of the loading frame to rotate in a direction calculated to move the material carried by the loading conveyor rearwardly. If the chain 102 should move in the opposite direction, caused by the reversal of the motor 19, the gear 111 will be rotated in the opposite direction, which will cause the ratchet teeth provided upon the hub of said gear to shift the sprocket 114 laterally, since it is manifest that the angle of said teeth and the direction of rotation of the gear 111 will not permit the sprocket 114 to rotate in unison with said gear. Hence, by so shifting the sprocket 114, the teeth provided upon the opposite face of the hub thereof will be brought into positive locking engagement with the ratchet teeth provided upon the hub of the sprocket 109, and hence the said sprocket 114 will be rotated positively in the required direction by power derived directly from the sprocket 109. If the teeth of the hub of the sprocket 114 should be so positioned, during the shifting of said sprocket, that the same will contact simultaneously with the tips or outer portion of the teeth provided in connection with the sprocket 109 and the gear 111, breakage is avoided by the provision of a spring 116, which is positioned so as to surround the shaft 108 and to be po-

sitioned between the gear 111 and the case 117 for the clutch. Thus, if the teeth should reach simultaneously these extreme positions of tooth engagement, the spring 116 will permit the gear 111 to yield in an outward direction 70 so that damage to parts will be avoided, however, when the sprocket teeth slip into proper position, the tension upon the spring 116 will be released, thereby permitting the parts to return to normal positions. By this construction it will be apparent that the motor 19 may be reversed so as to govern the direction of operation of the gathering conveyor, which feature is necessary when the gathering frame is being swung from one side to another, 80 but by reason of the automatic clutch construction described the loading conveyor will continue to force material outwardly of the hopper irrespective of the direction of movement on the part of the gathering conveyor, 85 and moreover, a common motor may be employed for operating both mechanisms.

It is frequently desirable to adjust the rear or discharge end of the loading frame with respect to the mine car 92. Since the hopper of the loading frame is mounted to swing about the horizontal pivot offered by the shaft 95, use is made of a frame raising and lowering construction 119. This construction consists in the provision of a pair of spaced brackets 119, which are mounted upon the bed plate 10, and to which are pivotally connected the lower ends of a pair of tubes 120. These tubes are normally vertically disposed and are adapted to telescopically receive a 100 pair of vertically disposed screws 121, the latter having their upper ends pivotally connected as at 122 with the loading frame. Arranged to threadedly receive the screws 121 and to rest upon the upper portions of the tubes 120 is a pair of threaded hubs 123, which are formed to include hand wheels 124, whereby when said wheels are rotated, the screws 121 will be caused to move vertically, thus effecting adjustments in the operative height 110 of the rear end of the loading frame. Preferably, the hubs are equipped with sprockets 125, around which is trained an endless chain 126, this construction being employed in order that when one of the wheels 124 is rotated, 115 both screws will be moved a corresponding distance. A suitable cross bracing 127, is connected with the tubes 120, so that both of said tubes will be firmly held in assembled relationship and caused to move in unison. 120 By pivotally mounting the lower ends of the tubes, it will be apparent that the frame raising and lowering construction can be adapted to the arc of travel of the loading frame. By this construction the loading frame may be raised and lowered to assume any desired working height, and also by the shaft 17 and associated parts, the bed plate and the loading frame may be bodily shifted in a lateral direction 125 so that the discharge end of the loading 130

frame will be capable of delivering material into mine cars situated side by side on parallel tracks.

Attention is particularly invited to the depressed forward end construction of the bed plate. By this construction it will be observed that the hopper may be positioned close to the tracks, a construction which renders it possible to reduce the effective height of the machine. Accordingly, by compacting or installing the parts of the machine in this manner the machine will require but low overhead clearance, and therefore the same may be employed for low vein mining work. The side 15 of the hopper 89 is preferably cut away so as to receive the rear end of the gathering mechanism, and these cut-away portions are adapted to be filled by means of removable or sliding plates 128, which may be so positioned as to prevent material thrown centrifugally from the gathering chain from falling out of the confines of the hopper. Also, another important feature of the present invention resides in forming the loading frame so that unnecessary noise, caused by the contacting of the loading chain with the floor 99 of the frame, will be reduced to a minimum. In machines of this nature the operation thereof has been attended by considerable noise, with the result that it has been a difficult matter to use the same for pillar robbing purposes, owing to the fact that when engaged in such work the noise of the machine has drowned the noises incident to ceiling cracks, which 35 noises are utilized for the purpose of warnings to the workmen to notify them of the falling condition of the mine roof. It is for this and other reasons that the various shafts of the machine have been equipped with anti-friction devices and conflicting or rubbing parts have been in many instances formed from different materials to diminish noisy operations. However, considerable difficulty has been encountered in rendering the operation 40 of the loading mechanism noiseless since the loading frame is in effect a drum-like structure wherein sound vibrations are amplified or augmented. To reduce or arrest such vibration, and consequently to diminish unnecessary sounds, the floor 99 of the loading frame is provided with a plurality of wooden bars 129, which are so correlated with respect to the floor 99 that the vibration thereof, caused by the passage of the flights 98 and the coal thereover, will be reduced to a minimum. The advantages of this noiseless construction are many, and in addition to that stated, the construction operates to enable the operators of the machine to readily hear spoken instructions, and eliminates the deafening clatter hitherto involved in machines of this nature.

In the operation of the gathering mechanism, it frequently occurs that the gathering chain will be overloaded, or will strike unresisting material. When this occurs a huge

strain is placed upon the gathering chain and its driving mechanism, which if not relieved, would have a detrimental effect upon the various driving parts thereof causing chain breakage, motor troubles and other disorders. 70

Accordingly, the relief clutch construction 23 is provided which operates to receive the power of the motor 19 and yet to prevent such power from being fully transmitted to the gathering mechanism when the latter is over-loaded, or when a predetermined load has been reached. To this end the gear 22 is loosely mounted around the shaft 24 and is disposed within a suitable case 128. This gear 22 is of peculiar construction and comprises a substantially hollow body wherein a disk compartment 129 is provided. This compartment is arranged to receive a plurality of flat multiple disks 130, which are situated concentrically with respect to the shaft 24, certain of the disks are keyed as at 131 to the gear 22, while the remaining disks are keyed as at 132 to a sleeve member 133 rigidly carried by the shaft 24. To control the frictional grip between the disks 130, the gear 22 is internally threaded as at 134, to receive a plate 135. This plate carries a plurality of brackets 136, which are so disposed as to receive pivotally a plurality of bell crank levers 137. These levers have their short arms equipped with rollers 138, and their longer arms are arranged to project into an annular groove provided in a shifting sleeve 139, the latter being connected with the lever 85, which is suitably fulcrumed so that by oscillating the same back and forth, the sleeve 139 may be reciprocated upon the end of the shaft 24. Manifestly, by forcing the sleeve 139 inwardly, the bell cranks will be swung about their pivots so that the rollers 138 thereof will be tightly forced by an arc movement into engagement with a pressure plate 140, which is disposed in engagement with the outer of the disks 130. When the rollers 140 are thus pressed into engagement with the plate 140, pressure will be imparted to the disk 130, thus connecting for rotation the gear 22 and the shaft 24. However, it is manifest that should the load on the gathering chain become excessive, the resistance offered by the shaft 24 to turning movement will be of such character that the disks will slip relatively, thus preventing the driving connections from being overloaded, and also preventing undue breakage of parts. By the construction recited it will be apparent that wear can be taken up in the clutch 23 by simply adjusting the positions of the plate 135, and also it will be apparent that there will be an absence of relative movement in a turning direction between the plate 140 and the rollers 138, since the plate 140 is keyed for rotation with the gear 22.

In view of the foregoing it will be apparent that the present invention provides a loading

machine capable of being efficiently used for the purpose of loading coal or other similar material from positions where the coal has been blasted or shot down into portable cars or to positions of storage. The machine has been designed with the view of rendering the same exceptionally portable and flexible, in order that the same may load material efficiently upon curved trackways, or in the tortuous rooms or passageways of a coal mine. Again, the machine is rendered convenient to manipulate by reason of the centralized controls and by virtue of other features, noise incident to its operation is believed to be reduced to a minimum. Again, by reason of the depressed forward end of the bed plate the height of the machine is reduced to such point that the machine may be usefully employed in the mining of low vein coal or ore. Attention is also directed to the automatic mechanism which is provided for controlling operation of the drums governing the feeding movement of the gathering mechanism, a construction which eliminates inaccessible manual controls, and, also, to the automatic clutch structure which allows the loading conveyor to operate rearwardly irrespective of the direction of rotation or operation of its controlling motor and the associated gathering mechanism.

While there has been illustrated and described the preferred form of construction for carrying this invention into effect, this is capable of variation and modification without departing from the spirit of the invention, therefore, it is not intended that the invention should be limited to the precise details of construction set forth but should be construed to cover and include such modifications as fall within the scope of the appended claims.

What is claimed is:

1. In a loading machine, a portable base unit, a gathering mechanism including a frame, a pivotal mounting between the rear end of said frame and said base unit whereby the frame may oscillate bodily about a vertical axis defined by said mounting, means for oscillating said frame, comprising a frame carried reversible motor, a shaft driven by said motor, a plurality of independently mounted cable drums, side feed cables connected with said drums, sprockets fixed to rotate with said shaft, other sprockets loosely rotatable in connection with said drums, independent chains between the drum sprockets and shaft sprockets, and reversely operating screw and clutch mechanism between said drums and the sprockets thereof, whereby said drum may be selectively rotated to wind and unwind said cables thereabout in accordance with the direction of rotation of said motor.
2. In a loading machine, a base unit, a gathering mechanism including a frame, a

pivotal mounting between the rear end of said frame and base unit whereby said frame may oscillate bodily about said mounting, means for oscillating said frame comprising a frame carried reversible motor, a shaft driven by said motor, a plurality of independently mounted longitudinally aligned cable drums, feed cables connected with said drums, power transmitting devices between said shaft and said drums, superposed spooling drums mounted above the forward of said drums and over which the cables connected with said drums are trained, and guide pulleys mounted in the lower portion of said frame and around which said cables are trained so as to project outwardly and laterally from said frame.

3. In a loading machine, a gathering mechanism including a reversible endless belt conveyor, a loading mechanism arranged to receive materials discharged from said conveyor, said loading mechanism including an endless belt, a reversible drive motor common to both of said belts, drive connections between said motor and belts, and automatically operating means co-operative with said connections for driving the forward run of said loading mechanism belt in an advancing direction irrespective of the direction of rotation of said motor or the direction of movement of said gathering belt.

4. In a loading machine, a portable base unit, gathering and loading mechanisms supported in conjunction with said base unit, a reversible motor operable to drive both of said mechanisms, and a clutch structure automatically operative to drive the loading mechanism in but one direction only irrespectively of the direction of rotation of said motor and the direction of movement of said gathering mechanism.

5. In a loading machine, a traveling base unit, a gathering mechanism including a frame, a pivotal mounting between said frame and base unit whereby the frame will be capable of swinging horizontally into engagement with the material to be loaded, a reversible gathering conveyor carried by the frame and capable of having its direction of movement regulated in accordance with the direction of feeding movement of said frame toward said material, a loading mechanism including an elevating conveyor carried by said base unit and capable of receiving material discharged from said gathering conveyor, a single reversible motor capable of driving both of said conveyors, and an automatically operating clutch structure between said motor and elevator conveyor, said structure being operable automatically to drive said elevator conveyor in but one direction irrespectively of the direction of rotation of the motor and the direction of movement of the gathering conveyor.

6. In a loading machine, a portable base

unit, gathering and loading mechanisms carried in conjunction with said base unit, a reversible motor for driving both of said mechanisms, and an automatically operable

5 clutch structure between said motor and loading mechanism for effecting rearward or discharge movement only on the part of said loading mechanism irrespectively of the direction of rotation of the motor and movement of the gathering mechanism.

10 7. In a loading machine, a gathering conveyer including a pair of spaced stationary run-ways, an endless reversible belt having laterally extending flight arms arranged to advance material in the line of draft of the machine along either of said run-ways, a hopper disposed to receive material discharged from the rear ends of said run-ways, a loading belt leading out of the bottom of 15 said hopper, a reversible operating motor common to both of said belts for effecting their operation, and automatically operating drive means between said motor and belts for driving the forward run of the loading belt in the line of draft of said machine irrespective of the direction of movement of the gathering belt over said run-ways.

20 8. In a loading machine, a gathering conveyer including a pair of stationary material conveying run-ways extending in the line of draft of the machine, an endless reversible belt having laterally extending flights arranged to advance material along either of said run-ways, a hopper situated to receive 25 material discharged from said run-ways, an endless loading belt having its forward run movable over the bottom of said hopper in the line of draft of the machine, a single motor for driving both of said belts, and drive connections between said motor and belts, said connections being formed to admit of the reversing of the direction of movement of said gathering belt without changing the direction of movement of said loading belt.

30 45 9. In a loading machine, a portable base unit, a gathering mechanism pivotally mounted in conjunction with said base unit, said mechanism including an elongated frame and an endless conveyor, a hopper carried by said base unit and capable of receiving material discharged from the gathering mechanism, a loading conveyor for leading material out of said hopper, a motor capable of driving both of said conveyors, a separate motor 40 carried by said frame for effecting lateral feed movements on the part of the frame, an overload clutch between said first named motor and gathering conveyor, and a pair of controls mounted upon said base unit for governing the operation of said motors, said controls being situated immediately adjacent to said overload clutch.

45 50 55 60 65 10. In a loading machine, a wheeled truck, a bed plate pivotally supported in conjunction with said truck, a gathering mechanism,

a loading mechanism mounted upon said plate and into which the gathering mechanism is adapted to discharge the material handled thereby, and a common motor carried by said plate and movable bodily therewith, 70 said motor being capable of imparting power to both said gathering and discharge mechanisms.

11. In a loading machine, a wheeled base unit, a bed plate supported pivotally for 75 horizontal swinging movement in connection with said base unit, a gathering conveyor having its rear end pivotally supported by the forward part of said bed plate, a hopper structure carried by said bed plate and into 80 which the material discharged from said gathering conveyor is received, a loading conveyor for leading material out of said hopper, and a common motor carried by said bed plate and operative to impart power to both 85 of said conveyors.

12. In a loading machine, a wheeled base unit, a bed plate having the forward portion thereof pivotally connected with said base unit, a gathering mechanism including a 90 frame and an endless conveyor, a vertical support for the rear end of said frame connected by a horizontal pivot with said bed plate, a swivel connection between said frame and said support, a driving shaft passing vertically through said support, a power element carried by the upper end of said shaft for imparting movement to said gathering conveyor, and a motor driven shaft for driving said vertical shaft, said motor driven shaft being disposed longitudinally of the horizontal axis of said support.

95 13. In a loading machine, a gathering mechanism including an endless reversible belt having laterally extending arms movable to advance material in unison with said belt through either of a pair of run-ways extending in the line of draft of the machine, said run-ways being alternately available in accordance with the direction of movement of

100 said belt, a loading mechanism including a hopper into which the material discharged from said gathering mechanism is received, an endless loading conveyer belt having the forward run thereof movable along the bottom of said hopper to lead material out of said hopper in the line of draft of the machine, an operating motor for driving both the gathering and loading mechanism belts, drive connections between said motor and belts, automatically operating means for driving said loading belt in a draft direction irrespective of the direction of movement of said gathering belt, and a combined cut-off and overload clutch in the connections between said motor and gathering conveyor belt, the said clutch being independent of the drive to the loading belt.

110 115 120 125 130 14. In a loading machine, a wheeled truck having a recessed forward end, a bed plate

having a lowered depressed forward end arranged to be pivotally mounted in the recessed portion of said truck, a gathering mechanism including a frame, a pivotal support between said frame and base plate, said support being located substantially in vertical coincidence with the pivotal connection between said plate and truck, a loading mechanism carried by said base plate, and a motor mounted upon said base plate for effecting the operation of said loading mechanism.

15. In a loading machine, a wheeled truck, a bed plate pivotally supported for horizontal swinging movement in connection with said truck, a hopper having its forward end pivotally connected with said bed plate, whereby said hopper may have its rear end adjusted vertically with respect to said truck and may be shifted bodily laterally by the movement 20 of said bed plate, a support for regulating the height of the rear end of said hopper, said support comprising a pair of tubular standards pivotally carried by the rear end of said bed plate, screw members having their upper 25 ends connected with said hopper, adjusting nuts carried by said screw members and cooperative with said standards to regulate the height of the rear end of said hopper, and means connecting said nuts to cause the latter to move in unison.

30. 16. In a loading machine, a wheeled truck, a shiftable bed plate mounted upon the upper surface of said truck, said plate having its forward end pivotally connected with said truck, gathering and loading mechanisms supported from said plate, anti-friction bearings between the rear end of said plate and said truck, a worm and rack mechanism operative to permit of the horizontal swinging 40 movements of said plate.

45. 17. In a loading machine, a wheeled truck, a loading mechanism carried by said truck including a hopper provided with a bottom and flaring side walls, an endless conveyor arranged to ride over said bottom between said walls, a motor for driving said conveyor, and means for deadening vibration on the part of the bottom of said hopper set up by the engagement of the conveyor therewith.

50. 18. In a loading machine, a portable base unit, a gathering mechanism including a frame having one end thereof mounted for pivotal movement in connection with said base unit, the other or free end of said frame being permitted to rotate about a vertical axis provided by said pivotal connection, means for moving said frame laterally to maintain the free end of the same in engagement with the material to be loaded, said 55 means comprising a motor carried by the frame, independent mechanisms carried by said frame and capable of oscillating the latter above its vertical pivot, and means automatically operable in accordance with the 60 direction of rotation of said motor to selec-

tively impart the power of the motor to said mechanisms.

19. In a loading machine, a gathering conveyer including a pair of spaced stationary run-ways extending in the line of draft of 70 the machine, a reversible endless conveyer belt arranged to advance material in a draft direction along either of said run-ways, a hopper arranged beneath the discharge ends of said run-ways, an endless elevator belt 75 having the forward run thereof movable along the bottom of said hopper to lead material in the line of draft of the machine out of said hopper, and to a relatively elevated point of discharge, a reversible operating 80 motor common to both of said belts, driving connections between said motor and belts, and an automatically operating mechanism serving in conjunction with said connections to drive the forward run of said elevator belt 85 in the line of draft of said machine irrespect- 90ive of the direction of rotation of said motor and the direction of travel of said gathering belt in conveying material over the alter- 95nately available run-ways of the gathering 90 conveyer.

20. In a loading machine, an elongated inclined gathering conveyer, a pivotal mounting for the relatively elevated discharge end of said conveyer, said mounting serving to 95 admit of lateral swinging movement on the part of the forward floor engaging end of the conveyer, means for effecting lateral swinging movement of said conveyer consisting of a reversible motor, a pair of winding elements, side feed cables having their inner ends connected with said elements and the outer ends thereof disposed for connection with relatively stationary anchors disposed laterally of said conveyer, and power 100 imparting means between said motor and winding elements automatically operative in accordance with the direction of rotation of the armature shaft of said motor to selectively control the operation of said elements. 110

21. In a loading machine, a portable base unit, a platform pivotally mounted upon said base unit and movable horizontally with respect thereto, a pair of transversely spaced supports formed with said platform, a hollow pedestal pivotally connected with said supports to swing about a horizontal axis, a motor driven drive shaft journaled in connection with said supports, the axis of said shaft being coincident with said horizontal 115 axis, a gathering conveyer frame pivotally mounted upon the upper end of said pedestal, for turning movement about an axis disposed perpendicularly to said horizontal axis, and endless conveyer carried by said frame, a drive shaft for said conveyer mounted to oscillate bodily with said pedestal, and drive gearing between the angularly disposed shafts of said supports and pedestals. 120

22. In a loading machine, a portable base unit, a platform pivotally provided upon said base unit and shiftable in a substantially horizontal plane with respect thereto, a pedestal pivotally connected with said platform to swing in a substantially vertical plane, a gathering mechanism pivotally mounted upon the upper part of said pedestal to oscillate in a vertical plane in unison with said pedestal and to swing in a horizontal plane about a vertical axis provided by said pedestal, the said vertical axis and the pivotal connection between said base unit and platform being disposed substantially in coincidence, a loading mechanism movable bodily with said platform and thereby maintained in operative relationship with said gathering mechanism, and motor driven drive connections extending through
- 5 said pedestal from said platform to the 20 gathering mechanism.
23. In a machine of the nature described, an elongated inclined gathering conveyor pivotally mounted at its upper rear end to permit the lower floor engaging end thereof 25 to sweep horizontally across the floor of a mine, cable reeling drums positively rotative in a cable reeling direction for respectively swinging said gathering conveyor in alternate directions, reversible power transmission means, and non-reversible clutch devices for said drums, whereby when said transmission means is rotative in one direction one of said drums is active and in a reverse direction the other of said drums is active. 30 35

In testimony whereof I affix my signature.

NORTON A. NEWDICK.
